UNITED STATES PATENT OFFICE.

LEWIS F. BETTS, OF NEW YORK, N. Y., ASSIGNOR TO ABBOT A. LOW, OF HORSESHOE, NEW YORK, AND MAURICE J. WOHL AND HARRY HERTZBERG, OF BROOKLYN, NEW YORK, TRUSTEES.

GAS-HEATER.

1,026,427.

Specification of Letters Patent.

Patented May 14, 1912.

Application filed March 25, 1910. Serial No. 551,413.

To all whom it may concern:

Be it known that I, LEWIS F. BETTS, a citizen of the United States, and resident of the city of New York, borough of Brooklyn, county of Kings, and State of New York, have invented certain new and useful Improvements in Gas-Heaters, of which the following is a specification.

This invention relates to gas heaters adapted for use with a gas burner using the ordinary illuminating gas.

The object of this invention is to provide a device of simple construction which may be easily and cheaply manufactured and which shall be efficient in cases where a small amount of heat is required.

In carrying out my invention I provide a device formed of a single flat disk in which by reason of the peculiar construction, the desired results are produced in a very simple and efficient manner.

A further object of the invention resides in the peculiar relation of the differently shaped portions of the device which enables the same to be packed or nested together so as to occupy the minimum amount of space for shipment. This feature also affords an additional protection of the device against damage in shipment and materially reduces the labor and cost of packing.

Figure 1 is a sectional view of a gas heater embodying my invention, taken about on the line 1—1 of Fig. 2. Fig. 2 is a plan view of Fig. 1, the burner being omitted.

The heating device shown in the drawing comprises a flat disk-shaped member 1, preferably constructed of noncombustible material, such as asbestos, with a metallic member 1^a inclosing the outer edge thereof. This member 1 is provided at its central portion with a hollow projecting portion 2, which is preferably constructed of metal and flaring so that when several of these devices are placed together these portions will fit one into the other. This hollow projecting portion 2 fits over the shell of the burner 3 and provides a support and means of attachment to the burner. The burner 3 is of peculiar construction, being provided with a chamber formed by cup-shaped members 4 and 5. These cup-shaped members 4 and 5 are formed with beaded portions around the adjoining edges thereof, one of which is pressed or spun over the other to secure the same together. This annular

projection or bead 6 upon the upper cup-shaped member 5 also provides a stop and support against which the projecting portion 2 of the heater is positioned and which assists in holding the same in a horizontal position. The lower portion of the burner 3 is provided with a tubular connection 7 for connecting the same to an ordinary gas fixture in the manner shown in Fig. 1. A number of small orifices 9' are provided in the lower cup shaped member 4, through which the gas passes and, when lighted, form a number of radially projecting jets which are drawn out by the currents of air, which spread outwardly under the flat surface of the heater, in radially extending flames which produce an intense heat. The projection 2 at the central portion of the disk shaped member 1 is provided at its upper portion with radially extending tongues 2' which are embedded in the non-combustible material from which the member 1 is made, the parts 2' in this manner firmly connecting the metallic member 2 with the member 1. It is to be noted also that the central aperture of the member 1 permits the heat from the burner 3 to pass direct to the article supported on the member 1. The flame of the burner does not contact directly with the article being heated because the upper cup shaped member 6 of the burner constitutes a closure or cap forming a metallic partition between the burner and such article.

The currents of heated air first follow the flat under surface of the heater and are then allowed to spread outwardly in a horizontal direction from the heating disk. The heated air is also drawn upwardly through the perforations 8, which are preferably arranged in a circle concentric with the center of the disk, and thus assists in the distribution of the same and also in the heating of the entire disk, which then gives off the heat in every direction.

Many experiments have been made in order to secure a cheap form of heater and the one herein shown and described has been found to give very efficient results. If the gas jets are lighted before the heater is placed in position on the burner the same will extend outwardly only a short distance, but immediately upon placing the heater in position on the burner the jets are drawn out to a greatly increased length thus show-

ing conclusively the operation of the air currents just described. The effect of these air currents is not only to extend the flame of the gas burner, but insures a continuous 5 and fresh supply of oxygen for combustion, thus producing a more intense heat for the same gas consumption.

While the form of heater and burner herein shown and described is believed to be the 10 most efficient for a cheap device, I do not wish to be understood as limiting myself to the exact form shown, as it is possible to produce heaters and burners of this type which may be modified somewhat in the 15 various details of construction and it is intended that this particular form shown shall be considered as illustrative of such modifications of the invention as may come within the scope of the appended claims and 20 not in a limiting sense.

What I claim is:

1. A gas heater comprising a flat disk of non-combustible substance formed with a central aperture, a hollow projection at the 25 central portion of said disk surrounding said aperture and converging downwardly therefrom, the upper end of said projection being formed with radiating tongues penetrating the disk from the under side to con-

nect the projection therewith, and a burner 30 comprising a hollow body having its upper portion partially removably received in the projection, the upper extremity of the body of the burner being closed and forming a partition below the central aperture of the 35 disk, and also provided with a number of small orifices below the lower end of said hollow projection, substantially as described.

2. A gas heater comprising a disk 40- provided with a central aperture and having a hollow projection extending therefrom and surrounding said aperture on the bottom of the disk, and a burner connected with said projection and partially received by the latter, said burner comprising an upper cup shaped member constituting that portion 45 which is received by the projection, and which member forms a partition at the upper end of the burner and below the central 50 aperture of the disk.

Signed at Brooklyn, N. Y., in the county of Kings and State of New York, this 23rd day of March, 1910.

LEWIS F. BETTS.
